TUNING INDICATOR SYSTEM

Harold L. Blaisdell, Little Neck, N. Y., assignor,
by mesne assignments, to Hazeltine Research,
Inc., Chicago, Ill., a corporation of Illinois

Application October 29, 1945, Serial No. 625,159

12 Claims. (Cl. 250—40)

1 The present invention relates to tuning indicator systems for wave-signal receivers and, particularly, to such systems for indicating the degree of mistuning of the receiver on either side of a received wave signal or for indicating the degree and direction of such mistuning.

Wave-signal receivers conventionally are provided with adjustable tuning elements by which the receiver may be tuned to a desired wave signal. Such tuning elements usually provide continuously adjustable tuning over a selected band of wave-signal frequencies. Inasmuch as inaccurate tuning of the receiver frequently results in undesirable distortion of the received wave-signal modulation components, the cause of which distortion may not be recognized by the listener, it is further conventional to provide the receiver with a visual tuning indicator by which the listener may more accurately tune the receiver to the desired wave signal.

Tuning indicator systems heretofore used or proposed for amplitude-modulation receivers include some device for visually indicating the magnitude of a unidirectional current or voltage derived from the wave signal translated by the receiver and varying with its amplitude. Tuning indicator systems for frequency-modulation receivers are somewhat similar to those for amplitude-modulation receivers except for the manner of deriving the tuning indicator control potential. The latter is usually so derived that the amplitude and polarity of the potential varies with the degree and direction, respectively, of mistuning of the receiver to the desired wave signal.

All such prior indicating systems are so arranged that the magnitude of indication provided by the system varies directly with the intensity of a received wave signal as translated to the point in the receiver where the tuning indicator control potential is derived. Wave signals of strongest intensity produce a large indication while wave signals of relatively weak intensity produce weak indications. It is thus characteristic of these prior systems that a relatively weak wave signal, while it has sufficient intensity that the modulation components derived therefrom by the receiver may be satisfactorily reproduced, does not have sufficient intensity to produce more than a perceptible tuning indication often inadequate to aid in accurately tuning the receiver. Even on received wave signals of moderate intensity, prior tuning indicator systems usually do not have the very high sensitivity which it would be desirable that they have at all times.

2 This is because the highest sensitivity of the system must be reserved for those wave signals having the largest intensities to be encountered in the operation of the receiver.

5 It is an object of the present invention, therefore, to provide a new and improved tuning indicator system, for a wave-signal receiver including an adjustable tuning means, which avoids one or more of the disadvantages and limitations of prior such systems.

10 It is a further object of the invention to provide a tuning indicator system which has an indicating sensitivity varying inversely with the intensity of received wave signals.

15 It is an additional object of the invention to provide a tuning indicator system which provides approximately the same magnitude of indication over a wide range of received wave-signal intensities.

20 It is a further object of the invention to provide a new and improved tuning indicator system, for a wave-signal receiver including an adjustable tuning means, of simple and inexpensive circuit arrangement involving a minimum of 25 circuit components.

25 In accordance with a particular form of the invention, a tuning indicator system, for a wave-signal receiver including an adjustable tuning means, comprises an input circuit adapted to have applied thereto a unidirectional control signal the magnitude of which varies with the degree of mistuning of the receiver on either side of a received wave signal, and a tuning indicator coupled to the input circuit and responsive to the control signal for indicating such degree of mistuning. The system includes means for deriving a control effect, the magnitude of which varies much less rapidly with the aforesaid degree of mistuning than does the aforesaid control signal, and for utilizing the control effect to vary inversely with the intensity of the received wave signal the sensitivity of response of the indicator to the control signal to reduce the sensitivity of indication thereof with increasing intensities of the received wave signal.

30 40 45 50 55 For a better understanding of the present invention, together with other and further objects thereof, reference is had to the following description taken in connection with the accompanying drawings, and its scope will be pointed out in the appended claims.

Referring now to the drawings, Fig. 1 is a circuit diagram, partly schematic, of a complete wave-signal receiver embodying the present invention in a particular form; Figs. 2 and 3 comprise curves

used as an aid in explaining the operation of the Fig. 1 arrangement; Fig. 4 illustrates several typical tuning indications produced for various assumed tuning conditions of the Fig. 1 receiver; Fig. 5 is a circuit diagram, partly schematic, of a portion of a wave-signal receiver embodying a modified form of the invention; Fig. 6 comprises curves used as an aid in explaining the operation of the Fig. 5 arrangement; and Fig. 7 is a circuit diagram, partly schematic, of a portion of a wave-signal receiver embodying an additionally modified form of the invention.

Referring now more particularly to Fig. 1 of the drawings, there is represented, partly schematically, a complete frequency-modulation wave-signal receiver of a conventional design embodying the present invention in a particular form. The receiver is shown as including a tunable radio-frequency amplifier 10 having an input circuit coupled to an antenna system 11, 12 and having an output circuit coupled to a tunable frequency changer or oscillator-modulator 13. Connected in cascade with the oscillator-modulator 13, in the order named, are an intermediate-frequency amplifier 14, a combined single-stage or multi-stage intermediate-frequency amplifier and automatic-volume-control or A. V. C. supply 15 (which may, if desired, include a conventional amplitude limiter), a frequency detector 16, an audio-frequency amplifier 17, and a sound reproducer 18. As is conventional in such receivers, the units 10 to 16, inclusive, have a relatively broad band-pass characteristic which may, for example, be 150 or 200 kilocycles wide. A tuning indicator system, presently to be described in greater detail, includes a tuning indicator device 19 is coupled to the output circuit of the frequency detector 16. The automatic-volume-control supply of unit 15 has an output circuit, designated as A. V. C., coupled to the input circuit of one or more of the tubes of units 10, 13, 14, and 15 in conventional manner.

It will be understood that the various units just described may, with the exception of the tuning indicator system, be of a conventional construction and operation, the details of which are well known in the art, rendering further description thereof unnecessary. Considering briefly the operation of the receiver as a whole, and neglecting for the moment the operation of the tuning indicator system presently to be described, a desired frequency-modulated wave signal is selected and amplified by the tunable radio-frequency amplifier 10, converted to a frequency-modulated intermediate-frequency wave signal in the oscillator-modulator 13, amplified in the intermediate-frequency amplifiers 14 and 15, and detected by the frequency detector 16, thereby to derive the audio-frequency modulation components thereof. The audio-frequency components, are in turn, amplified in the audio-frequency amplifier 17 and are reproduced by the sound reproducer 18 in conventional manner. An automatic-volume-control or A. V. C. bias derived by the A. V. C. supply system of unit 15 is effective to control the amplification or gain of one or more of the units 10, 13 or 14 to maintain the signal input to the detector 16 within a relatively narrow range for a wide range of received signal intensities.

Referring now more particularly to the portion of the wave-signal receiver embodying the present invention, the tuning indicator system includes an input circuit, comprising input-circuit terminals 20, adapted to have applied thereto a

unidirectional tuning control signal the magnitude of which varies with the degree of mistuning of the receiver on either side of the received wave signal and the polarity of which varies with the direction of such mistuning. Where the unit 15 includes a conventional limiter to limit amplitude variations of a received wave signal, the control signal applied to the input terminals 20 also varies with the intensity of the wave signal for all values thereof less than the limiting level. This condition occurs, for example, when receiving wave signals from comparatively distant transmitting stations. It is the purpose of the present invention to provide tuning indications of approximately the same magnitude for reception from such stations as for reception from less distant stations which, because of the larger intensities of their received wave signals, cause amplitude limiting to be effected by the limiter. If no limiter is provided in the unit 15, the magnitude of the signal applied to the input terminals varies, for any degree of mistuning, with the intensity of the received wave signal but over a much wider range of intensities than occurs when a limiter is used. The tuning indicator system also includes the tuning indicator 19 which is coupled through an amplifier and phase inverter 21 to the input terminals 20 and is responsive to the tuning control signal applied thereto for indicating the degree and direction of mistuning of the receiver to the received wave signal. In particular, the indicator 19 is of the cathode-ray tube type having an anode or target electrode 22 and including input electrodes comprising a cathode 23 and a pair of cathode-ray beam deflecting electrodes 24 and 25. The deflecting electrodes 24 and 25 of the indicator tube 19 are directly connected respectively to a screen electrode 26 and an anode 27 of tube 21, the screen electrode 26 and anode 27 being energized from a source of potential, indicated as +B, through respective resistors 28 and 29. The tube 21 includes a pair of input electrodes, comprising a suppressor electrode 30 and a cathode 31, which are coupled through a filter network including a series-arm resistor 32 and a shunt-arm condenser 33 to the input-circuit terminals 20. The indicator system thus far described is of the type shown and described in the United States Letters Patent No. 2,294,182, granted August 25, 1942 to Robert T. Hintz, for "Tuning indicator for carrier-signal receivers," and assigned to the same assignee as the present invention.

The tuning indicator system of the present invention also includes means for deriving a control effect, the magnitude of which over the pass band of the receiver varies much less rapidly with the degree of mistuning of the receiver than does the aforementioned control signal, and for utilizing the control effect to vary inversely with the intensity of the received wave signal, by variation of the energization of the anode or target electrode 22 of the indicating tube 19, the sensitivity of response of the indicator 19 to the tuning control signal applied to the input-circuit terminals 20 to reduce the sensitivity of indication of the tube 19 with increasing intensities of the received wave signal. This means comprises the intermediate-frequency amplifier 14 which includes a vacuum-tube repeater 34 having input electrodes, including a control electrode 35, coupled through a double-tuned band-pass selector 36 to the output circuit of the oscillator-modulator 13. The repeater 34 has an anode 37 coupled through a double-tuned band-pass selector

38 to the input circuit of the intermediate-frequency amplifier 15. The last-mentioned means also includes means for utilizing the aforementioned control effect to vary inversely with the intensity of a received wave signal an operating characteristic, namely the transconductance, of the repeater 34, thereby correspondingly to vary the gain of the amplifier 14. This means comprises the automatic-volume-control bias source of the unit 15, which derives an A. V. C. bias or control effect, and the automatic-volume-control circuit, designated A. V. C., which is coupled to the control electrode 35 of the repeater 34 through a filter network including a series resistor 39 and shunt condenser 40. The indicator sensitivity-control means additionally includes means responsive to variations of the operating characteristic of repeater 34, namely, to variations of its transconductance or to variations of gain of the amplifier 14, for controlling in accordance therewith the sensitivity of response of the indicator tube 19 to the tuning control potential applied to the input terminals 20 to reduce the sensitivity of indication of the indicator tube 19 with increased intensities of the received wave signal. The last-mentioned means comprises a positively energized screen electrode 41 provided in the repeater 34, a resistor 42 which is serially included between the screen electrode 41 and its energizing source, indicated as +Sc, a by-pass condenser 43 connected between the screen electrode 41 and ground, and an energizing circuit 44 for energizing the anode or target electrode 22 of the indicator tube 19 from the positively energized screen electrode 41 of the repeater 34.

In considering the operation of the tuning indicator system just described, reference is made to the curves of Figs. 2 and 3 and to the illustrative tuning patterns of Fig. 4. A detailed description of the general operation of that portion of the indicator system which includes tubes 19 and 21 is contained in the aforementioned Hintz patent. Briefly considered, for purposes of the present description, assume that the receiver has a conventional band-pass characteristic represented by curves A or B of Fig. 2, this characteristic being relatively flat-topped over a frequency range f_1 to f_2 centered about a frequency f_0 which represents the mean resonant frequency of the intermediate-frequency selectors of the receiver, for example the selectors 36 and 38. Curve A is representative of the response for a received wave signal of large intensity while curve B represents the response for a wave signal of relatively weak intensity. Since the intensity of a received wave signal translated to the A. V. C. supply of unit 15 varies with tuning in accordance with the band-pass characteristic of the receiver, the curves A and B are also representative of the variation of the derived control effect or A. V. C. bias with tuning of the receiver across a received wave signal respectively having a large intensity or a weak intensity. The frequency-response characteristic of the frequency detector 16 is represented by curve C for a received wave signal of large intensity and by curve D for a wave signal of relatively weak intensity, the detector characteristic thus being of the familiar S configuration centered upon and varying rapidly in the region of the mean resonant frequency f_0 of the receiver.

Assume now that the receiver is accurately tuned to a desired wave signal so that the frequency-modulated intermediate-frequency wave signal of the receiver has a mean wave-signal

frequency f_0 . Under the foregoing assumed conditions, the audio-frequency filter 32, 33 removes any audio-frequency modulation components developed in the output circuit of the frequency detector 16 and, since the average output potential of the detector is then zero as indicated by either of the curves C or D, no unidirectional tuning-control signal is applied to the input electrodes 30, 31 of the tube 21. For this operating condition, the values of the screen resistor 28 and anode resistor 29 of the latter tube are so selected with relation to the normal operating currents of the screen and anode electrodes that there are applied to the deflecting electrodes 24 and 25 of the indicator tube 19 positive potentials of equal amplitudes. Each of the deflecting electrodes 24 and 25 produces an individual "shadow angle" on the fluorescent target electrode 22, the size of each shadow angle varying with the magnitude of the control potential applied to the deflecting electrodes. The manner in which the shadow angle varies, assuming a constant potential of approximately 150 volts applied to the fluorescent anode 22, with variation of potential applied to one of the deflecting electrodes 24 or 25, is represented by curve E of Fig. 3. With equal potentials applied to the deflecting electrodes, the resultant "shadow angles" are equal and the deflection pattern which appears on the fluorescent anode of tube 19 is symmetrical, as illustrated by the pattern of Fig. 4a, wherein the shadow angles are represented by the dark areas F and G and the equal luminous areas are represented by the light portions H and I. This symmetrical pattern provides a visual indication that the receiver is accurately tuned to the received wave signal.

Assume now that the receiver is mistuned to one side of the received wave signal. The output of the frequency detector 16 now has an average unidirectional component of potential the magnitude of which is dependent upon the degree of mistuning and the polarity of which is dependent upon the direction of mistuning. Here again the audio-frequency filter 32, 33 removes the audio-frequency modulation components so that only the unidirectional component alone is applied to the input electrodes 30, 31 of the tube 21. If this unidirectional potential has a positive polarity, it increases the anode current and decreases the screen-electrode current of the tube 21 thus to increase the screen-electrode potential and decrease the anode potential. The magnitude of such potential change varies, of course, with the magnitude of the unidirectional potential applied to the input electrodes of the tube 21. The positive unidirectional potentials applied to the deflecting electrodes 24 and 25 of the indicator tube 19 are now no longer equal, one having been increased by a certain amount and the other having been decreased by approximately the same amount. This unequal energization of the deflecting electrodes 24 and 25 produces an unsymmetrical deflection pattern on the fluorescent anode of the indicator tube 19. The resulting indication is as indicated by Fig. 4b, which represents the visual indication produced by mistuning of the receiver to one side of the received wave signal, or by Fig. 4c which represents the visual indication produced by mistuning of the receiver to the opposite side of the received wave signal. There is thus provided by the several shadow angles and luminous areas on the fluorescent target electrode 22 of the indicator device 19 independent visual indications which indicate both the degree or magnitude and

the direction of mistuning of the receiver from the desired wave signal.

As previously mentioned, the automatic-amplification-control or A. V. C. bias derived from the A. V. C. supply of unit 15 is applied through the filter 39, 40 to the control electrode 35 of the vacuum-tube repeater 34 so to vary its gain, in conjunction with a similar variation of gain of units 10 or 13 as to maintain the signal input to the frequency detector 16 within a relatively narrow range for a wide range of received signal intensities. In so doing, the A. V. C. bias reduces the space current of the screen electrode 41 of the repeater 34 with increasing intensities of the received wave signal. Since the space current of the electrode 41 flows through the resistor 42 to develop thereacross a potential drop, it will be apparent that the positive potential energization of the screen electrode 41 varies directly with the intensity of the received wave signal. However, the anode or target electrode 22 of the indicator tube 19 is energized, through the energizing circuit 44, from the screen electrode 41 of the receiver 34. It will thus be apparent that the positive energizing potential applied to the target electrode 22 of the indicator tube 19 also varies directly with the intensity of the received wave signal.

In the absence of a received wave signal, or when only a weak intensity wave signal is received, little or no A. V. C. bias is developed by unit 15 with the result that the potentials of the screen electrode 41 of tube 34 and the target electrode 22 of the indicator tube 19 have minimum values. The electrons emitted by the cathode 23 of the latter tube are attracted to the target electrode 22 thereof with relatively low velocities so that the electron beam is "soft" and easily deflected through large angles with small changes of potentials applied to the deflecting electrodes 24 and 25. The response characteristic of the indicator tube 19 for a low, but constant, value of target-electrode potential is represented by curve J of Fig. 3. Increasing the positive energization of the target electrode 22, as with increasing values of A. V. C. bias consequent upon increasing intensities of a received wave signal, effects a corresponding increase in the velocity of the electrons emitted by the cathode 23 and travelling to the target electrode 22. As a result, the beam becomes "stiffer" and a larger change of potential on the deflecting electrodes 24 and 25 is required to produce a given change of the shadow angle on the fluorescent screen of the target electrode 22. Each of curves K, E and L of Fig. 3 represents an individual, different response characteristic of the indicator tube 19 for a given individual, constant value of potential applied to the target electrode 22, the several values of potential increasing from that for which curve K is representative to that for curve L. These curves make evident the fact that increasing energization of the target electrode effects decreasing sensitivities of the indicator tube, particularly, in that larger values of energization make it necessary to apply larger values of control signal to the deflecting electrodes 24 and 25 to effect a given change of the shadow angle.

Now it will be apparent that while increasing values of wave-signal intensity produce larger values of A. V. C. bias and correspondingly larger positive energizations of the target electrode 22 of tube 19, thus to change inversely with the wave-signal intensity the sensitivity of response of the

latter tube, the slope of the frequency-detector characteristic correspondingly increases with the value of the wave-signal intensity as earlier pointed out in connection with curves C and D of Fig. 2. As a result, any deviations of the mean frequency of a received wave signal from the mean intermediate frequency f_0 , as would occur for example during tuning of the receiver, produce unidirectional tuning control signals (which are applied to the tube 21 and thus to the deflecting electrodes 24 and 25 of the indicator tube 19) the magnitudes of which increase directly with the intensity of the received wave signal. Such larger control signals then effectively counteract the decreasing response sensitivity of the indicator tube 19 and cause approximately the same change of shadow angle for either strong intensity or weak intensity received wave signals.

The value of the screen resistor 42 of the amplifier 14 is so selected with relation to the screen potential $+Sc$ and the characteristics of the tubes 34 and 19 that the response characteristic of the indicator tube 19 would be that represented by the broken-line curve M of Fig. 3 if the changes of target-electrode potential and changes of tuning control signal applied to the tube 21 both were to vary simultaneously and proportionately with the received wave-signal intensity.

This, however, is not the actual operation of the tuning indicator system since the derived A. V. C. bias has a value which varies, with the tuning of the receiver, as represented by curves A or B of Fig. 2. The A. V. C. bias is thus substantially constant over the frequency range f_1 to f_2 , whereas the tuning control signal varies rapidly in magnitude on either side of the frequency f_0 and over the frequency range f_1 to f_2 . The constant value of A. V. C. bias developed over the frequency range f_1 to f_2 results in a constant value of energization of the target electrode 22 of the indicator tube 19, the exact value of energization varying with the intensity of the received wave signal as hereinbefore pointed out, so that over this frequency range the latter tube operates with a response sensitivity represented by one of its characteristic curves J, K, E or L of Fig. 3. Thus, as the tuning control signal applied to the tube 21 varies over the frequency range f_1 to f_2 in accordance with the characteristic curves C or D of Fig. 2 depending upon the received signal intensity, the entire tuning indication provided by the tube 19 over the same frequency range follows along one of the characteristic curves J, K, E or L of Fig. 3 from the 90-degree shadow-angle value to a minimum shadow-angle value at which the particular sensitivity curve intersects the broken-line curve M.

A sharp tuning indication is thus provided, the maximum change of the shadow angle of tube 19 being approximately the same whether the received wave signal has weak intensity or relatively strong intensity. For this reason, the tuning indications thus provided enable as high an accuracy of tuning of the receiver to wave signals of weak intensity as to wave signals of strong intensity, particularly in that the maximum response of the indicator system need no longer be reserved, as heretofore necessary, for the highest intensity wave signal to be encountered in the operation of the receiver.

Fig. 5 is a circuit diagram, partly schematic, of a portion of a wave-signal receiver of the amplitude-modulation type embodying the present invention in a modified form. The present arrangement is essentially similar to that of Fig. 1,

similar circuit elements being designated by similar reference numerals and analogous circuit elements being designated by similar reference numerals primed, except that the receiver includes an amplitude detector and A. V. C. supply 16' for deriving the amplitude-modulation components of a received wave signal and for deriving a conventional A. V. C. bias. The tuning indicator tube 19' of the present arrangement is of a type conventionally used in amplitude-modulation receivers and may, for example, be of the 6E5 type which includes a triode section comprising a cathode 23', a control electrode 45, and an anode 46. The anode has internally connected thereto a deflecting electrode 24' and the indicator tube includes a target electrode 22' cooperating with the deflecting electrode. The anode 46 is connected to the target electrode 22' through a resistor 47 and the target electrode is energized through the energizing circuit 44 from the screen electrode 41 of the vacuum-tube repeater 34.

The tuning indicator system of the present arrangement also includes a tuning signal supply 48 having a sharply tuned parallel-resonant circuit 49 of high Q, or high ratio of inductive reactance to resistance, tuned to the mean intermediate frequency f_0' of the amplifiers 14 and 15. The resonant circuit 49 preferably has a band-pass characteristic much narrower than that of the overall band-pass characteristic of the receiver, for example a pass band of two or three kilocycles where the receiver pass band is 10 kilocycles. The resonant circuit 49 is enclosed within a wave-signal shield, indicated by the broken line surrounding it, to reduce direct pick-up by the circuit of wave-signal energy and is coupled to the output circuit of the amplifier 15 by a small coupling condenser 50 of one or two micromicrofarads capacitance. This small value of capacitance is desirable to minimize the reaction of the resonant circuit 49 on the resonant coupling circuits of the units 15 and 16'. A rectifier device 51 and rectifier load impedance, comprising a resistor 52 and shunt condenser 53, are serially connected across the resonant circuit 49. The resistor 52 preferably has a value of resistance of several megohms so that it does not appreciably load, and thereby decrease the Q of, the resonant circuit 49. The condenser 53 has sufficient capacitance that the time constant of this condenser and the resistor 52 is long in comparison with the period of the lowest-frequency modulation component of the received wave signal so that the modulation components are effectively removed by the condenser 53 and resistor 52. The resistor 52 and condenser 53 are connected between the control electrode 45 and the cathode 23' of the indicator tube 19'.

The operation of this modified form of the invention is essentially similar to that of Fig. 1. In considering its operation, reference is made to the curves of Fig. 6 where curve N represents the band-pass characteristic of the receiver for a received wave signal of relatively strong intensity and curve O that for a received wave signal of relatively weak intensity. This band-pass characteristic is assumed to have a relatively broad and nearly flat top over the frequency range f_1' to f_2' centered upon the mean intermediate frequency f_0' . Similarly, the band-pass characteristic of the resonant circuit 49 is represented by the curve P, Fig. 6, for a received wave signal of strong intensity and by curve R for a received wave signal of relatively weak intensity. It will be seen that the resonant circuit 49 is tuned to

the mean intermediate frequency f_0' and that its band-pass characteristic is much narrower than that of the receiver.

The A. V. C. bias developed by the A. V. C. supply of unit 16' has a value which, as the receiver is tuned across a given received wave signal, varies in accordance with the band-pass characteristic of the receiver. It will be thus apparent that curves N and O also represent the magnitude of A. V. C. bias developed, with tuning of the receiver, respectively to a strong wave signal and to a weak wave signal. This A. V. C. bias so controls the potentials of the screen electrode 41 of the tube 34 and of the target electrode 22' and anode 46 of the indicator tube 19', for reasons pointed out in connection with Fig. 1, that the curves N and O may also be considered to represent the variation of energization of the specified electrodes of these tubes with tuning of the receiver across a strong received wave signal and a weak received wave signal, respectively.

It will thus be seen that the energizations of the target electrode 22' and anode 46 of the indicator tube 19' remain substantially constant over the tuning range f_1' to f_2' of the receiver. Consequently, the sensitivity of response of the tuning indicator tube may be represented by one of the curves J, K, E or L of Fig. 3, depending upon the intensity of the received signal, as explained in connection with the operation of the Fig. 1 arrangement.

The tuning signal-supply system 48 rectifies the wave-signal energy applied thereto from the output circuit of the intermediate-frequency amplifier 15 to develop across its load impedance 52, 53 a unidirectional potential or tuning signal, free from modulation components, which is applied to the control electrode 45 of the indicator tube 19' to provide a tuning indication. Since this tuning signal changes rapidly in magnitude over the tuning range f_1' to f_2' of the receiver, and has a maximum value at the mean intermediate frequency f_0' , whereas the energization of the tuning indicator tube 19' is substantially constant over this tuning range, it will be apparent that the entire tuning indication is effected along one of the response curves J, K, E, or L of Fig. 3 as established by the magnitude of the A. V. C. bias developed by unit 16' and thus by the intensity of a received wave signal.

As in the arrangement of Fig. 1, a wave signal of relatively weak intensity, for example one which establishes a sensitivity of the indicator tube 19' as represented by curve J of Fig. 3, causes a smaller tuning signal to be developed by the supply system 48. The latter signal may be represented, for example, by the curve R of Fig. 6. Now while the maximum magnitude of this signal is relatively small, it will be noted that the response sensitivity of the indicator tube 19', represented by curve J of Fig. 3, is very high so that the small tuning signal is able to produce a large change of shadow angle of the indicator tube. On the other hand, a received wave signal of relatively strong intensity, which for example establishes a sensitivity of the indicator tube 19' as represented by curve L of Fig. 3, produces a larger tuning signal in the system 48, for example such as that represented by curve P of Fig. 6, so that the larger signal is effective to produce a large change of the shadow angle of the indicator tube 19'. In practice, the circuit components of the tuning indicator system may be so selected that the tuning indication provided by the in-

icator tube 19' at the mean intermediate frequency f_0 is substantially the same for received wave signals of weak intensity as for received wave signals of strong intensity. There consequently is no necessity for so operating the tuning indicator system that the maximum response of the system be reserved for the highest intensity wave signal to be encountered in the operation of the receiver.

It may be noted that the anode 46 of the indicator tube 19' is also energized from the screen electrode 41 of the repeater tube 34, thus effecting a greater amplification of the tuning signal applied to the control electrode 45 for higher intensity wave signals. In certain applications, it may be desirable that the anode 46 of tube 19' be energized through the resistor 47 from a source of potential +B, rather than from the screen electrode 41, in order to maintain uniform the amplification provided by the triode section 23', 45 and 46 of tube 19'.

Experience has shown that for uniformity of tuning indication over a wide range of received wave-signal intensities, it is preferable that the A. V. C. supply of unit 16' be of the conventional delay-bias type. The value of delay bias to be used is established with relation to the intensity of a relatively weak intensity wave signal such as that which causes operation of the indicator tube 19' along curve J of Fig. 3. For this wave-signal intensity, the value of delay bias used is preferably such that no A. V. C. bias is developed by the A. V. C. supply of unit 16' until the shadow angle of tube 19' has closed to approximately 45 degrees while tuning the receiver toward the wave signal.

An additional operating characteristic of both the Figs. 1 and 5 tuning indicator systems may be mentioned. This relates, as explained above in connection with the arrangement of Fig. 1, to the change of brightness of fluorescence of the target electrode 22 or 22' with the intensity of a received wave signal. That is, wave signals of larger intensity effect an increase of the target luminous intensity in accordance with the A. V. C. bias developed by the supply system of unit 16 or 16' thus further to aid in the tuning operation of the receiver. For example, while tuning toward a desired wave signal an increase of luminous intensity of the target electrode at once provides an indication that the desired wave signal is being received even though no tuning indication is yet provided by the indicator tube. The tuning operation is then completed by the indication furnished by the latter tube.

Fig. 7 is a circuit diagram, partly schematic, representing an additionally modified form of the invention essentially similar to that of Fig. 5. Similar circuit elements are designated by similar reference numerals and analogous elements by similar reference numerals double primed. Here the indicating device 19'' of the present arrangement comprises an indicating meter. The latter has a field-energizing winding 54 included in the cathode circuit of the vacuum-tube repeater 34 and has a movable winding 55 mechanically connected to an indicating needle 56 and coupled to the tuning signal supply 48.

The operation of this modified form of the invention is essentially similar to that of Fig. 5 except that the automatic-volume-control or A. V. C. bias applied to the control electrode 35 of the vacuum-tube repeater 34 effects a change of the space currents of both the anode 37 and screen electrode 41. Since the space currents

of these electrodes flow through the cathode circuit of tube 34 and thus through the field winding 54 of the indicating device 19'', there is effected a change of sensitivity of the device 19'' with changes of wave-signal intensity. Thus received wave signals of large intensity, which produce a large A. V. C. bias and effect a substantial reduction of the space current of the repeater 34, effect a correspondingly large reduction of the electromagnetic field produced by the meter winding 54. The large tuning signal then applied to the deflecting winding 55 effects a movement of the indicating needle 56 through approximately the same angle as would occur with a received wave signal of much lesser intensity which, in developing a smaller A. V. C. bias, permits a larger energizing current to flow through the winding 54 and a larger magnetic field to be developed thereby. The operation of this modified form of the invention is otherwise essentially similar to that of Fig. 5 and will not be repeated.

It will be apparent from the above description of the invention that a tuning indicator system embodying the invention has an indicating sensitivity varying inversely with the intensity of a received wave signal so that it provides approximately the same magnitude of indication over a wide range of received wave signal intensities. The tuning indicator system of the invention has the additional advantage that it is of simple and inexpensive circuit arrangement involving a minimum of circuit components.

While there have been described what are at present considered to be the preferred embodiments of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a tuning indicator coupled to said input circuit and responsive to said control signal for indicating said degree of mistuning, and means for deriving a control effect the magnitude of which varies much less rapidly with said degree of mistuning than does said control signal and for utilizing said control effect to vary inversely with the intensity of said received wave signal the sensitivity of response of said indicator to said control signal to reduce the sensitivity of indication thereof with increasing intensities of said received wave signal.

2. A tuning indicator system for a wave-signal receiver including an adjustable tuning means comprising, an input circuit adapted to have applied thereto a control signal the magnitude of which varies both with the intensity of a received wave signal and with the degree of mistuning of said receiver over individual tuning ranges on either side of said received wave signal, a tuning indicator coupled to said input circuit and responsive to said control signal for indicating said degree of mistuning, and means for deriving a control effect the magnitude of which varies with the intensity of said received

wave signal but varies much less rapidly with said degree of mistuning than does said control signal and for utilizing said control effect to vary inversely with the magnitude thereof the sensitivity of response of said indicator to said control signal to reduce the sensitivity of indication thereof with increasing intensities of said received wave signal.

3. A tuning indicator system for a wave-signal receiver including an adjustable tuning means comprising, an input circuit adapted to have applied thereto a control signal the magnitude and polarity of which vary with the degree and direction, respectively, of mistuning of said receiver over individual tuning ranges on either side of a received wave signal, a tuning indicator coupled to said input circuit and responsive to said control signal for indicating said degree and direction of mistuning, and means for deriving a control effect the magnitude of which varies much less rapidly with said degree of mistuning than does said control signal and for utilizing said control effect to vary inversely with the intensity of said received wave signal the sensitivity of response of said indicator to said control signal to reduce the sensitivity of indication thereof with increasing intensities of said received wave signal.

4. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a cathode-ray tube tuning indicator having input electrodes coupled to said input circuit and responsive to said control signal for indicating said degree of mistuning, and means for deriving a control effect the magnitude of which varies much less rapidly with said degree of mistuning than does said control signal and for utilizing said control effect to vary inversely with the magnitude thereof the energization of said cathode-ray tube so to control the sensitivity of response of said indicator to said control signal as to reduce the sensitivity of indication thereof with increasing intensities of said received wave signal.

5. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a cathode-ray tube tuning indicator having an anode and including input electrodes coupled to said input circuit and responsive to said control signal for indicating said degree of mistuning, and means for deriving a control effect the magnitude of which varies much less rapidly with said degree of mistuning than does said control signal and for utilizing said control effect to vary inversely with the magnitude thereof the energization of said anode to reduce the sensitivity of indication of said indicator with increasing intensities of said received wave signal.

6. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a cathode-ray tube tuning indicator having a cathode-ray target elec-

trode and including at least one deflecting electrode coupled to said input circuit and responsive to said control signal for deflecting the cathode-ray beam of said indicator to indicate said degree of mistuning, and means for deriving a control effect the magnitude of which varies much less rapidly with said degree of mistuning than does said control signal and for utilizing said control effect to vary inversely with the intensity of said received wave signal the energization of said target electrode to reduce the sensitivity of indication of said indicator with increasing intensities of said received wave signal.

7. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a tuning indicator coupled to said input circuit and responsive to said control signal for indicating said degree of mistuning, a vacuum-tube repeater, means for deriving a control effect the magnitude of which varies much less rapidly with said degree of mistuning than does said control signal and for utilizing said control effect to vary inversely with the intensity of said received wave signal an operating characteristic of said repeater, and means responsive to variations of said operating characteristic for controlling in accordance therewith the sensitivity of response of said indicator to said control signal to reduce the sensitivity of indication thereof with increasing intensities of said received wave signal.

8. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a tuning indicator coupled to said input circuit and responsive to said control signal for indicating said degree of mistuning, a vacuum-tube repeater, means for deriving a control effect the magnitude of which varies much less rapidly with said degree of mistuning than does said control signal and for utilizing said control effect to vary inversely with the intensity of said received wave signal the transconductance of said repeater, and means responsive to variations of said transconductance for controlling in accordance therewith the sensitivity of response of said indicator to said control signal to reduce the sensitivity of indication thereof with increasing intensities of said received wave signal.

9. A tuning indicator system for a wave-signal receiver including an adjustable tuning means comprising, an input circuit adapted to have applied thereto a control signal the magnitude of which varies with the degree of mistuning of said receiver over individual tuning ranges on either side of a received wave signal, a tuning indicator coupled to said input circuit and responsive to said control signal for indicating said degree of mistuning, a vacuum-tube repeater having a positively energized electrode, means for deriving a control effect the magnitude of which varies much less rapidly with said degree of mistuning than does said control signal and for utilizing said control effect to vary inversely with the intensity of said received wave signal the energization of said electrode, and an energizing circuit for energizing said indicator from said posi-

tively energized electrode to vary inversely with the intensity of said received wave signal the sensitivity of response to said indicator to said control signal to reduce the sensitivity of indication thereof with increasing intensities of said received wave signal.

10. A tuning indicator system for a wave-signal receiver including an adjustable tuning means and a gain-controllable wave-signal amplifier comprising, an input circuit adapted to have applied thereto a control signal the magnitude of which varies with the degree of mistuning of said receiver over individual tuning ranges on either side of a received wave signal, a tuning indicator coupled to said input circuit and responsive to said control signal for indicating said degree of mistuning, means for deriving a control effect the magnitude of which varies much less rapidly with said degree of mistuning than does said control signal and for utilizing said control effect to vary inversely with the intensity of said received wave signal the gain of said amplifier, and means responsive to variations of the gain of said amplifier for controlling in accordance therewith the sensitivity of response of said indicator to said control signal to reduce the sensitivity of indication thereof with increasing intensities of said received wave signal.

11. A tuning indicator system for a wave-signal receiver including an adjustable tuning means and having a relatively broad band-pass characteristic for received wave signals comprising, an input circuit adapted to have applied thereto a control signal the magnitude of which over at least the central portion of said band pass of said receiver varies rapidly with the degree of mistuning of said receiver over individual tuning ranges on either side of a received wave signal, a tuning indicator coupled to said input circuit and responsive to said control signal for indicating said degree of mistuning, and means for deriving a control effect the magnitude of which over said band of said receiver varies

much less rapidly with said degree of mistuning than does said control signal and for utilizing said control effect to vary inversely with the intensity of said received wave signal the sensitivity of response of said indicator to said control signal to reduce the sensitivity of indication thereof with increasing intensities of said received wave signal.

12. A tuning indicator system for a wave-signal receiver including an adjustable tuning means and having a relatively broad band-pass characteristic for received wave signals comprising, means including a sharply resonant circuit having a band-pass characteristic substantially less than that of said receiver for deriving a control signal the magnitude of which over at least the central portion of said pass band of said receiver varies rapidly with the degree of mistuning of said receiver over individual tuning ranges on either side of a received wave signal, a tuning indicator coupled to said means and responsive to said control signal for indicating said degree of mistuning, and means for deriving a control effect the magnitude of which over said pass band of said receiver varies much less rapidly with said degree of mistuning than does said control signal and for utilizing said control effect to vary inversely with the intensity of said received wave signal the sensitivity of response of said indicator to said control signal to reduce the sensitivity of indication thereof with increasing intensities of said received wave signal.
